Specification of Letters Patent.

Patented Feb. 5, 1918.

Application filed September 8, 1916. Serial No. 118,970.

To all whom it may concern:

Be it known that I, CALVIN B. PATCH, a citizen of the United States, residing at Glenellyn, in the county of DuPage and State of Illinois, have invented a certain new and useful Improvement in Two-Part Yokes, of which the following is a full, clear, concise, and exact description, reference being had to the accompanying drawings, forming a part of this specification.

This invention relates to improvements in two-part yokes.

The object of this invention is to provide a two-part yoke for railway draft riggings wherein the parts are duplicates of each other and having means for easily connecting with and disconnecting the same from a standard draw bar whether the latter is provided with coupler key slots or not.

20 In the drawing forming a part of this specification, Figure 1 is a side elevation of a yoke and draw bar showing my improvements in connection therewith. Fig. 2 is a horizontal sectional view taken on the line 25 2—2 of Fig. 1. Fig. 3 is a front end elevation of the yoke. And Fig. 4 is a rear end elevation of the yoke.

In said drawing, 10 denotes a draw bar, the butt of which is provided with usual 30 upper shoulder 11 and lower shoulder 12. The improved yoke, as shown, comprises two like members A, A, each of which consists of a horizontal arm 13, rear integral section 14, transversely extending shoulder 35 15 at its front end arranged to coöperate with one of the shoulders of the draw bar, and parallel side plates 16—16 overlapping the sides of the draw bar. The rear portions 14—14 of the two yoke members are provided with meshing perforated lugs 17 to receive a pivot pin 18, whereby the members A, A are pivotally connected at the rear. The side plates 16—16 of the yoke members are also provided with overlapping 40 45 perforated lugs or ears 19—19 to receive removable, longitudinally extending locking pins 20. The pins 18 and 20 are held in

position by any suitable means such as the cotters 21—21.

To disconnect the draw bar from the yoke 50 with the parts as shown in Fig. 1, it is apparent that it is only necessary to remove the pins 20 whereupon the lower member A of the yoke can be dropped down and the draw bar disengaged from the upper yoke member. 55

From the preceding description, it will be seen that the yoke may be manufactured at relatively small expense since only one pattern is employed; the yoke is adapted for use with all standard draw bars, regardless of the presence or absence of a coupler key slot; and the yoke parts may be locked and unlocked with ease since the pins 20 are accessible at the forward end of the gear. 65

I claim:

1. A yoke of the character described comprising two members movably connected at their rear ends, said members having means at their forward ends for operatively engaging a draw bar, the forward ends of said arms being provided with overlapping portions at the sides thereof, and detachable means extending horizontally and parallel to the axis of the yoke through said overlapping portions to thereby maintain the parts in operative position, said means being removable by movement in a direction parallel to the axis of the yoke. 70 75

2. A two-part yoke comprising members 80 movably connected at their rear ends, each of said parts having means for operatively engaging a draw bar, said parts having side portions at their forward ends adapted to overlie the sides of the draw bar butt, and independent means on each side of the yoke located entirely outside of the side planes of the draw bar butt for detachably connecting said portions to thereby hold the parts in operative engagement with the draw bar. 85 90

In witness that I claim the foregoing, I have hereunto subscribed my name this 5th day of Sept. 1916.

CALVIN B. PATCH.
